UNITED STATES PATENT OFFICE.

EDWIN P. CARPENTER, OF PAWTUCKET, RHODE ISLAND.

ROTARY EXPLOSIVE-ENGINE.

No. 898,965.

Specification of Letters Patent. Patented Sept. 15, 1908.

Application filed October 19, 1907. Serial No. 398,278.

To all whom it may concern:

Be it known that I, EDWIN P. CARPENTER, a citizen of the United States, and resident of the city of Pawtucket, in the county of 5 Providence, State of Rhode Island, have invented certain new and useful Improvements in Rotary Explosive-Engines, of which the following is a specification.

My invention relates to rotary engines in 10 which the motive power is obtained by the expansive action of gasolene vapor in which the ignition is automatically produced by electricity; and the principal object of my invention is to provide a novel form of engine 15 in which a series of explosive chambers are carried by a revoluble disk, secured on the engine-shaft, and arranged in such manner that the charge of gasolene vapor in each chamber is ignited at a point near to and beyond 20 the peripheral surface of the disk, in order that the expansive power of the actuating fluid will be fully utilized.

A further object of my invention is to provide an engine of simple and economical construction, and consists of the novel arrangement and combination of parts, as herein-after described and claimed.

In the accompanying drawings, Figure 1 represents a top plan view of a rotary engine 30 constructed in accordance with my invention. Fig. 2 is a side elevation of the engine, showing its gearing arrangement. Fig. 3 is an enlarged longitudinal sectional view of the engine, taken in line 3.—3. of Fig. 1, 35 illustrating the position the operating parts assume at the moment of ignition charge in one of the explosive chambers. Fig. 4 is a top plan sectional view, taken in line 4.—4. of Fig. 1, showing an explosive chamber and 40 compressor shaft respectively, as after the latter has forced a charge of gasolene vapor within said chamber, and, Fig. 5 is a top plan sectional view, taken in line 5.—5. of Fig. 1, showing the electric spark plug with an explosive chamber, as at the moment the gas 45 charge has been fired.

Like reference numerals indicate like parts.

The bed-plate 1 of the engine has integral standards 2, 2 provided with bearings 3, 3 for 50 the reception of the engine-shaft 4. Between the bearings 3, 3 and keyed on the shaft 4, is a disk 5, one quarter of whose peripheral portion is made to fit close within a recess 6 (see Fig. 4) formed in a curved extension 7 integral of the standards 2.

In the circular face of the disk 5 and

formed longitudinally thereof, is provided four sockets 8, 8, which are divided equidistant apart throughout the circle of the disk, and in these sockets are pivotally mounted 60 explosive shells for receiving and discharging a gasolene or other actuating vapor, and each shell is constructed as follows: Referring to Figs. 3 and 5, 9 represents the explosive shell, which has one end pivoted on a tube 10. 65 This tube 10 is driven through and fits snug in the side walls of the socket 8 and has a closed end to form a head 11, which abuts the side of the disk. The shell 9 is bored transverse of its pivot center to provide an 70 explosive chamber 12. A movable member is mounted in the shell, and said member comprises a piston 13 to fit the chamber 12; a conical spring 18 whose large end bears against a shoulder 14 of a bore 15 concentric 75 to the chamber 12 and its smaller end against a shoulder formed on the piston stem 16, which passes through a cap 17. This cap 17 is provided with a screw-threaded portion to engage a threaded portion of the bore 15 of 80 the shell. The spring 18 tends to force outward the stem of the piston after the shell has been fired. The shell 9 is provided with an intake or discharge opening 19 communicating with the chamber 12, and said shell is 85 also provided with a vent opening 20 communicating with said chamber 12 and registering with an opening formed in the side of the tube 10. Each shell, constructed as described, is mounted in like order throughout 90 the circle of the disk, and when each shell is in its respective socket its upper or exposed surface curves to conform with the circular face of the disk. The upper portion of the extension 7 of the engine-frame terminates 95 with an integral head 21 which is provided with a bore 22 extending transversa of and in axial alinement with the axial center of the engine-shaft 4. Within this bore 22 is mounted a compressor-shaft 23, which has 100 a fixed stud 24 secured at its outer end portion. On a fixed stud-shaft 25, secured in a standard 2, of the engine-frame, is loosely mounted a pinion-gear 26, which meshes with a large gear 27 keyed on the engine-shaft 4. On the hub of the pinion-gear 26 is made fast an eccentric 28, having strap 29, and connection 30 to the stud of the compressor-shaft 23. The head 21, of the engine-frame, has a hub 31 which is provided with a 105 small bore therethrough and communicating with the bore 22 of said head, as at 32, in

Fig. 4. An intake-pipe 33, from a carburetor (not shown) connects with the bore 32 of the hub 31. On a standard 2 of the engine-frame is secured a block of mica or 5 ether suitable insulating material, as 34, and on this material is secured one end of a flat spring 35 whose free end is arranged to contact with the head 36 of the center ignition rod of a spark plug. Each chamber 12 is 10 fired by a spark plug, as shown in Fig. 5, said plug having its body portion 37 screw-threaded to engage thereby in a threaded opening formed through a boss 38 integral of and concentric to the pivot center 20 of 15 the shell 9. I use the ordinary make of spark plug, except that I provide the center ignition rod 39 to slide in its insulating tube 40, and interpose an expanding coil spring 41 to surround said rod between the usual mica 20 washers 42, 42, and this difference in structure is to permit the sparking points of the rod 39 and terminal post 46 to be brought in contact with each other, through action of spring 41, and thereby unite the electric 25 circuit. In the structure in Fig. 3 I represent what is termed a "four cycle engine", that is to say, by the arrangement of the explosive shells, the firing of the same takes place at each quarter revolution of the disk 5. 30 The operation of my improved rotary engine is as follows: The disk 5 revolves in the direction indicated by the arrow 43 in Fig. 3, and as the driving gears 26, 27, which are in the proportion of 4 to 1, cause the compressor-shaft 23 to be actuated upon by the eccentric-connection 30, said shaft is carried forward from its dotted position beyond the vapor inlet 32, to its full line position shown in said figure, the amount of gasolene vapor 35 which filled the chamber 22 prior to this movement, will be forced into the chamber 12 of the shell 9, and thereby causing the end of the piston-stem 16 to come in contact with the end face of the socket 8 of the shell. 40 After the aforesaid shell has received its charge of gasolene vapor it is carried below the disk 5, and to a point slightly beyond the face of an abutment 44, integral of the engine-frame. The disk 5 is provided with 45 a coil push-spring 45, located beneath each shell 9, and as the latter reaches the point beyond the abutment 44, as specified, the action of the spring 45 swings the shell outwardly from its socket to an angular position 50 below said disk, and against a shoulder formed at the pivot-end portion of the shell, as at a point 47 in Fig. 3. At the moment the shell assumes this outward position upon the disk, as described, the head 36 of the 55 ignition rod 39 will be forced inwardly, by its coming in contact with the blade 35, in the manner shown in Fig. 5, thus freeing the ignition points of the rod 39 and post 46 and causing a spark firing for the vapor charge 60 65 in the shell. As the bearing point 16 of the

piston is beyond the peripheral surface of the disk 5 at the moment of firing, the expansive force created by the exploded vapor causes the piston to receive a rearward thrust toward and against the abutment 44 70 of the engine-frame, and this thrust produces a forward rotative movement of the disk 5. After the shell has been fired the action of the spring 18 of the piston causes the stem 16 of the latter to project from the cap 17 of 75 the shell, and thus the piston 13 will have moved to a point where the intake 19 will be in open communication with the explosive chamber 12, to the position of parts as represented at the left of Fig. 3. When the shell 80 comes in contact with the curved surface of the extension 7 the projecting stem of the piston will strike against the upper portion of the inclined surface of the socket 8, as at a point 53 at the top of Fig. 3, by this time the 85 intake 19 will be in open communication with the chamber 22, for the shell to receive the compressed charge of vapor through compressor-shaft 23. After the shell is so charged the stem 16 in moving down the inclined surface 53 of the socket causes a closing of the intake or port 19 by the piston of said stem, and this last movement causes a still further compression of the vapor to be had within the shell. Referring to Fig. 3, 90 the electric current operates as follows: The spring 35, which contacts with the spark plug, is electrically connected with the pole of a battery 48 by a wire 49, and from the pole of the battery 48 a wire 50 connects with 100 a spark coil 51, and from said coil 51 a wire 52 is connected to the bed-plate 1 of the engine-frame. Therefore, by my construction and arrangement of parts, I provide means whereby the shell receives a double 105 compression upon its vapor charge prior to firing, at each quarter revolution of the disk 5, which acts in the capacity of a balance or driving wheel, and at the same time each explosion of vapor in the shell takes place at 110 a point where the highest degree of efficiency and leverage is had.

Having described my invention, what I claim and desire to secure by Letters-Patent, is—

1. In a rotary explosive engine, the combination of the engine-bed having standards provided with bearings to receive the engine-shaft, and said bed disposing a curved grooved extension, which has an abutment 120 at one end thereof and its opposite portion provided with an intake-chamber to receive the actuating vapor; a compressor-shaft mounted in the intake-chamber; a revoluble disk secured on the engine-shaft and having its peripheral surface arranged to contact in the grooved extension of the engine-bed, and said disk provided with sockets formed in its peripheral surface; a shell pivotally mounted 125 in each socket of the disk and provided with 130

- an explosive-chamber; a spring actuated piston mounted in the chamber of each shell; a gearing arrangement to impart a reciprocating movement to the compressor-shaft to cause each shell to be charged with the actuating vapor; a spark plug mounted at the pivot center of each shell, and means to ignite the vapor in each shell that the thrust upon the piston by the explosion will be given 5 against the abutment of the engine-bed.
2. In a rotary explosive engine, the combination of the engine-bed formed in one casting, having standards provided with bearings to receive the engine-shaft, and a curved extension terminating with an outwardly projecting head, which is provided with a bore communicating with an intake passage; a disk made fast on the engine-shaft and having its circular face in contact with the surface 10 of the bed-extension, and said disk provided with a series of sockets formed in its face; explosive shells pivotally mounted in the sockets; means mounted in the disk to swing outwardly said shells; a spring-actuated piston in each shell; a shaft mounted in the head of the engine-bed; means to move last mentioned shaft whereby each shell is caused to be charged with an actuating vapor; a spark plug mounted at the pivot center of each shell and each plug having its center ignition rod slidable, and electrically controlled means mounted on the engine-bed to force the rod from contact with the terminal post of each plug and thus explode the 15 vapor charge in the shell and cause the piston of the latter to thrust against the engine-bed at a point below its curved extension.
3. In a rotary explosive engine, the combination of the engine-frame having an extension disposing a curved bearing surface; a disk secured on the engine-shaft and having its circular face in contact with the bearing surface of the extension; a plurality of explosive shells pivotally mounted in the circular face of said disk and each shell having a spring-actuated piston; an intake chamber; means to charge each shell with an actuating vapor when it reaches said chamber; means to swing outwardly each shell to permit its 20 piston to strike against an abutment of the engine-frame; an electrically-actuated spring blade secured on the engine-frame; and a spark plug mounted at the pivot center of each shell and each plug having a spring-actuated ignition rod to come in contact with said blade and cause a spark firing for the vapor charge in the shell.
4. In a rotary explosive engine, the combination of a rotatable disk provided with a series of sockets arranged in its circular face; a tube secured through the walls of each socket; an explosive shell mounted on the tube of each socket; means to automatically charge each shell with an actuating vapor; a spring-actuated piston in each shell; a 25 spark plug having a spring-actuated ignition rod; and electrically controlled means mounted on the engine-frame for the head of said rod to come in contact with and cause a spark firing for the charge in the shell. 70
5. In a rotary explosive engine, the combination of the engine-frame having a curved body portion which terminates with an abutment at one end and an intake chamber at the other portion thereof; a disk having its peripheral surface in contact with the curved portion of the engine-frame; a plurality of shells pivotally mounted in the peripheral surface of said disk; a spring-actuated piston movable in the explosive chamber of each shell; means to automatically charge each shell with an actuating vapor at the moment the shell arrives at the intake chamber; an electrically charged spring blade secured on the engine-frame; and a spark plug for each shell and each plug to contact with said blade, whereby the explosion of vapor takes place the moment the shell leaves the curved portion of the engine-frame, and permits its piston to strike against the abutment of the latter. 75 80 85 90
6. In a rotary explosive engine, the combination of the engine-frame having a curved extension integral with a head which is provided with an intake-chamber; an intake-pipe communicating with said chamber; a rotatable disk mounted on the engine-shaft and having its face in contact with the curved portion of the engine-frame; a shell pivoted on the disk and provided with an explosive 95 chamber and also an inlet from said chamber to communicate with the intake-chamber; a piston mounted in the chamber of said shell; a compressor-shaft in the intake-chamber; means to move said shaft and thereby charge the shell with an actuating vapor. 100 105
7. In a rotary explosive engine, the combination of the engine-frame having an abutment; an electrically controlled spring blade 110 mounted on said frame; a disk rotatably mounted on the engine-shaft and provided with a socket formed in its peripheral surface; a tube secured through the walls of the socket and provided with a vent; a shell 115 pivoted on said tube and provided with an explosive chamber which communicates with the vent of said tube, and also provided with a discharge opening; a cap secured on the end of said shell; a piston movable in the 120 chamber of said shell and having an integral stem projecting through said cap to strike against the abutment of engine-frame; means to force the stem of said piston from said cap; a push spring mounted in the disk 125 to bear against said shell; a spring-actuated spark plug mounted on said disk and arranged to come in contact with said blade whereby a spark firing is obtained in the tube. 130

8. In combination, the herein described rotary explosive engine, comprising a rotatable disk whose face is in contact with a curved portion of the engine-frame; a plurality of shells pivotally mounted in the peripheral portion of said disk and each shell provided with an explosive chamber; a spring-actuated piston movable in the chamber of each shell; means to doubly compress a vapor charge in each shell; means to cause the piston of each shell to come into contact with the

abutment of engine-frame; electrically controlled means for spark firing the charge in each shell after the piston in the latter strikes the abutment of the engine-frame. 15

In testimony whereof I affix my signature in presence of two witnesses.

EDWIN P. CARPENTER.
